[57] ABSTRACT

Compounds of the formula I are disclosed:

In the above formula, R₁ and R₂ represent hydrogen, lower alkyl, lower alkoxy, aryl, and halogen, or R₁ and R₂ taken together with the benzene ring may form an additional aromatic or heteroaromatic nucleus.

17 Claims, No Drawings

2-HYDROXY-2-METHYLSULFONYL)-
ACETOPHENONE ACETATES AND RELATED
COMPOUNDS

The present invention relates to novel compounds and, more particularly, the present invention relates to compounds of the formula I:

wherein R_1 and R_2 taken together with the benzene ring, form an additional aromatic or heteroaromatic nucleus.

In the above definitions for R_1 and R_2 the term "lower alkyl" and the alkyl portions of alkoxy are meant to have one to six carbon atoms. These are, for example, methyl, ethyl, propyl, isopropyl, butyl, isobutyl and the like. The term "aryl" denotes an aromatic hydrocarbon having six to 10 carbon atoms such as phenyl or tolyl. The term halogen encompasses fluorine, bromine, chlorine and iodine. The additional aromatic or heteroaromatic nucleus denotes such as naphthalene, isoquinoline, quinoline, and the like.

The compounds of this invention are useful as gastric antisecretory agents. At the dose level of 20 mg/kg intraperitoneally these compounds cause a 50-60% decrease in the volume of gastric acid in the rat, when tested according to the method described by Shay, et al. in *Gastroenterology* 5, 43 (1945) and Winter, et al., in *Proc. Soc. Exper. Biol. and Meds.*, 111, 544 (1960).

These compounds are indicated in the management of gastric hyperacidity such as gastric ulcer in mammals. In human beings, for example, a dose of 20 mg/kg orally or by injection two or three times daily is recommended. This dose regimen can be varied depending on the severity of the condition, age and sex of the patient being treated by methods known to the healing arts.

In addition, those compounds wherein R_1 is hydrogen and R_2 is methyl or wherein R_1 and R_2 taken together with the benzene ring form a naphthalene ring system, at the dose level of 100 mg/kg administered intraperitoneally exhibit the property of suppressing selectively the delayed hypersensitivity immunological response in mice. The primary immunological response is not affected, which leaves the vital anti-infective defense mechanisms unimpaired.

The test procedures involved are described by Jerne, et al., in *Cell-bound Antibodies*, Wistar Institute Press 1963, p. 109. Thus, these compounds may be useful in conditions associated with delayed hypersensitivity states such as arthritis.

In order to use these compounds, they are combined with excipients such as lactose, and formulated into dosage forms such as tablets by known pharmaceutical technology. They are also formulated into dosage forms with excipients such as water for injection suitable for parenteral administration.

According to the present invention, compounds of type I are prepared by the acetylation of compounds of type II according to the following sequence:

The starting materials II are synthesized by the oxidation of compounds of type III which are described in our copending Pat. application Ser. No. 174,947, entitled "Substituted o-hydroxymethylsulfinylacetophenones and Related Compounds." Generally speaking, the oxidation step is effected at ambient temperature and the product is recovered by conventional means. The step involving treatment of the product with acetic anhydride is also effected at ambient temperature and again the product is recovered by conventional means.

In order to further illustrate the practice of this invention, the following examples are included. Temperatures referred to therein are given in degrees Centigrade.

EXAMPLE 1

2'-Hydroxy-2-(methylsulfonyl)-3'-phenylacetophenone

A mixture of 16 g. of 2'-hydroxy-2-(methylsulfinyl)-3'-phenylacetophenone, 300 ml. of CHCl_3 , and 13 g. of m-chloroperbenzoic acid was stirred for one-half hr. The temperature rose to 45°. The solution was gently boiled for one-half hr., chilled, and stirred with 100 ml. of saturated NaHCO_3 solution. The organic phase was separated, dried over Na_2SO_4 , and evaporated to an oil under reduced pressure. On cooling the oil crystallized, and was recrystallized from abs. ethanol; m.p. 144°-145.5°; yield 14 g. (83%).

Anal. Calcd. for $\text{C}_{15}\text{H}_{14}\text{O}_4\text{S}$: C, 62.05; H, 4.86; S, 11.04. Found: C, 61.79; H, 4.98; S, 11.13.

EXAMPLE 2

3'-Hydroxy-2-(methylsulfonyl)-2'-acetonaphthone acetate

A mixture of 10 g. of 3'-hydroxy-2-(methylsulfinyl)-2'-acetonaphthone, 50 ml. of acetic anhydride, and 0.5 ml. of pyridine was stirred for 2 hr. The mixture was poured into 800 ml. of ice water and the mixture was

stirred for 1 hr. The precipitated solid was filtered off, washed with cold water, and recrystallized from CH_3CN ; m.p. 162°–164°; yield 7.0 g. (60%).

Anal. Calcd. for $\text{C}_{15}\text{H}_{14}\text{O}_5\text{S}$: C, 58.81; H, 4.61; S, 10.47. Found: 59.06; H, 4.90; S, 10.70.

EXAMPLE 3

2'-Hydroxy-6'-methoxy-2-(methylsulfonyl)acetophenone acetate

A mixture of 5 g. of 2'-hydroxy-6'-methoxy-2-(methylsulfonyl)acetophenone, 50 ml. of acetic anhydride and 0.25 ml. of pyridine was stirred for 6 hr., allowed to stand overnight, stirred for 4 additional hours, poured into 400 ml. of ice water, and stirred for 1 hr. The precipitate was filtered off, washed with cold water, and recrystallized from methanol; m.p. 87.5°–90°; yield 3 g. (53%).

Anal. Calcd. for $\text{C}_{12}\text{H}_{14}\text{O}_6\text{S}$: C, 50.34; H, 4.93; S, 25.11.20. Found: C, 50.17; H, 4.93; S, 11.33.

EXAMPLE 4

2'-Hydroxy-5'-methyl-2-(methylsulfonyl)acetophenone

A mixture of 35 g. of 2'-hydroxy-5'-methyl-2-(methylsulfonyl)acetophenone, 1.5 l. of CHCl_3 , and 35 g. of m-chloroperbenzoic acid was stirred for one-half hr. The temperature rose to 45°. The mixture was gently boiled for one-half hr, chilled, and stirred for 10 min. with 300 ml. of saturated NaHCO_3 solution. The organic phase was separated, and taken down to a solid under reduced pressure. The solid was then recrystallized from abs. ethanol; m.p. 146°–147°; yield 27 g. (72%).

Anal. Calcd. for $\text{C}_{10}\text{H}_{12}\text{O}_4\text{S}$: C, 52.62; H, 5.30. Found: C, 52.55, H, 5.46.

EXAMPLE 5

2-Hydroxy-5'-methyl-2-(methylsulfonyl)acetophenone acetate

A mixture of 10 g. of 2'-hydroxy-5'-methyl-2-(methylsulfonyl)acetophenone, 50 ml. of acetic anhydride and 0.5 ml. of pyridine was stirred for 1.5 hr. The solution was poured into 800 ml. of ice water, and the mixture was stirred for 1 hr. The precipitated solid was filtered off, washed with cold water and recrystallized from methanol; m.p. 104.5°–105.5°; yield 5.5 g. (46%).

Anal. Calcd. for $\text{C}_{12}\text{H}_{14}\text{O}_5\text{S}$: C, 53.32; H, 5.22; S, 11.86. Found: C, 53.47; H, 5.22; S, 11.76.

5

EXAMPLE 6

3'-Chloro-2'-hydroxy-2-(methylsulfonyl)acetophenone

A mixture of 50 g. of 3'-chloro-2'-hydroxy-2-(methylsulfonyl)acetophenone, 1.5 l. of CHCl_3 , and 50 g. of m-chloroperbenzoic acid was stirred for one-half hr. The temperature rose to 50°. The mixture was gently boiled for one-half hr., chilled, and stirred for 10 min. with 300 ml. of saturated NaHCO_3 solution. The organic phase was separated and evaporated to a solid under reduced pressure. This was recrystallized from abs. ethanol; m.p. 124.5°–125.5°; yield 50 g. (96%).

Anal. Calcd. for $\text{C}_9\text{H}_8\text{ClO}_4\text{S}$: C, 43.47; H, 3.65; S, 12.89. Found: C, 43.33; H, 3.67; S, 12.85.

EXAMPLE 7

30

3'-Chloro-2'-hydroxy-2-(methylsulfonyl)acetophenone acetate

A mixture of 10 g. of 3'-chloro-2'-hydroxy-2-(methylsulfonyl)acetophenone, 50 ml. of acetic anhydride and 0.5 ml. of pyridine was stirred for 1 hr. The solution was poured onto 800 ml. of ice water and the mixture was stirred for 1 hr. The precipitate was filtered off, washed with cold water, and recrystallized from CH_3CN ; m.p. 154°–158°; yield 9.5 g. (82%); λ_{max} μ (ε) 225 (24,000), 298 (5,200); ν_{max} 805 (ms), 920 (m), 1030 (m), 1135 (ms), 1190 (ms), 1210 (s), 1695 (ms), 1760 (s) cm^{-1} .

Anal. Calcd. for $\text{C}_{11}\text{H}_{11}\text{ClO}_4\text{S}$: C, 45.45; H, 3.81; Cl, 12.19; S, 11.03. Found: C, 45.51; H, 3.89; Cl, 12.04; S, 10.95.

EXAMPLE 8

50

2'-Hydroxy-3'-methoxy-2-(methylsulfonyl)acetophenone

A mixture of 30 g. of 2'-hydroxy-3'-methoxy-2-(methylsulfonyl)acetophenone, 750 ml. of CHCl_3 , and 33 g. of m-chloroperbenzoic acid was stirred for one-half hr. The temperature rose to 50°. The solution was boiled gently for one-half hr., chilled, and stirred 10 min. with 200 ml. of saturated NaHCO_3 solution. The organic phase was separated, and the aqueous phase extracted three times with 50 ml. portions of CHCl_3 . Combined organic phase and extracts were evaporated to a solid residue under reduced pressure. The residue

55

was recrystallized from abs. ethanol; m.p. 142°-143°; yield 24 g. (74%); λ max $m\mu$ (ϵ) 220 (16,000), 270 (9,300), 343 (2,400); ν max 735 (m), 780 (m), 840 (m), 970 (m), 1015 (ms), 1140 (m), 1255 (s), 1620 (ms) cm^{-1} .

Anal. Calcd. for $\text{C}_{10}\text{H}_{12}\text{O}_5\text{S}$: C, 49.17; H, 4.95; S, 13.13. Found: C, 49.43; H, 4.99; S, 13.02

EXAMPLE 9

2'-Hydroxy-3'-methoxy-2-(methylsulfonyl)acetophenone To a mixture of 10 g. of 2'-hydroxy-3'-methoxy-2-(methylsulfonyl)acetophenone and 50 ml. of acetic anhydride was added several drops of pyridine and the mixture was stirred. After one-half hr. a clear solution formed, and after 1 hr. a crystalline precipitate deposited. The mixture was poured into 800 ml. of ice water, and the mixture was stirred for 1 hr. The mixture was filtered, and the precipitate was recrystallized from methanol; m.p. 106°-107°; yield 9 g. (77%); λ max $m\mu$ (ϵ) 227 (20,600), 251 (11,600), 305 (4,000); ν max 790 (ms), 920 (m), 1005 (ms), 1125 (s), 1185 (ms), 1210 (ms), 1280 (ms), 1295 (s), 1590 (m), 1700 (ms), 1760 (s) cm^{-1} .

Anal. Calcd. for $\text{C}_{12}\text{H}_{14}\text{SO}_6$: C, 50.34; H, 4.93; S, 11.20. Found: C, 50.37; H, 5.02; S, 11.26.

EXAMPLE 10

1'-Hydroxy-2-(methylsulfonyl)2'-acetonaphthone A mixture of 50 g. of 1'-hydroxy-2-(methylsulfonyl)-2'-acetonaphthone, 1.5 l. of CHCl_3 , and 50 g. of m-chloroperbenzoic acid was stirred for one-half hr. The temperature rose to 45°. The mixture was gently boiled for one-half hr., chilled and stirred for 10 min. with 300 ml. of saturated NaHCO_3 solution. The organic phase was separated and evaporated to a crystalline residue under reduced pressure. The residue was recrystallized from abs. ethanol; m.p. 159°-161°; yield 44 g. (83%); λ max $m\mu$ (ϵ) 217 (27,300), 260 (31,100), 287 (7,100), 298 (9,100), 309 (5,750), 385 (5,800); ν max 805 (ms), 905 (m), 975 (ms), 1045 (ms), 1160 (ms), 1270 (ms), 1615 (ms) cm^{-1} .

Anal. Calcd. for $\text{C}_{13}\text{H}_{12}\text{O}_5\text{S}$: C, 59.08; H, 4.58; S, 12.13. Found: C, 59.03; H, 4.64; S, 12.29.

EXAMPLE 11

1'-Hydroxy-2-(methylsulfonyl)-2'-acetonaphthone acetate

A mixture of 10 g. of 1'-hydroxy-2-(methylsulfonyl)-2'-acetonaphthone, 50 ml. of acetic anhydride, and 0.5 ml. of pyridine was stirred for 1 hr. The resulting paste was stirred with 800 ml. of ice water for 1 hr., and the precipitated solid was filtered off, washed with cold water and recrystallized from ethyl acetate; m.p. 137°-139°; yield 8.5 g. (73%); λ max $m\mu$ (ϵ) 218 (38,500), 252 (27,200), 297 (5,700), 327 (3,900), 341 (4,200); ν max 790 (m), 830 (ms), 910 (m), 1045 (ms), 1160 (ms), 1210 (s), 1690 (ms), 1760 (s), cm^{-1} .

Anal. Calcd. for $\text{C}_{15}\text{H}_{14}\text{O}_5\text{S}$: C, 58.81; H, 4.61; S, 10.47. Found: C, 58.89; H, 4.65; S, 10.50.

EXAMPLE 12

5'-Fluoro-2'-hydroxy-2-(methylsulfonyl)acetophenone A mixture of 27 g. of 5'-fluoro-2'-hydroxy-2-(methylsulfonyl)acetophenone, 1.5 l. of CHCl_3 , and 30 g. of m-chloroperbenzoic acid was stirred for one-half hr. The temperature rose to 45°. The solution was gently boiled for one-half hr., chilled, and stirred for 10 min. with 200 ml. of saturated NaHCO_3 solution. The organic phase was separated and evaporated to a solid under reduced pressure. The solid was recrystallized from abs. ethanol; m.p. 120.5°-122.5°; yield 25 g. (86%); λ max $m\mu$ (ϵ) 255 (7,450); 357 (4,300); ν max 750 (m), 745 (ms), 840 (m), 975 (m), 1140 (s), 1195 (s), 1230 (ms), 1625 (ms); 1640 (ms) cm^{-1} .

Anal. Calcd. for $\text{C}_9\text{H}_9\text{FO}_4\text{S}$: C, 46.55; H, 3.91; S, 13.81. Found: C, 46.74; H, 4.03; S, 13.90.

EXAMPLE 13

5'-Fluoro-2'-hydroxy-2-(methylsulfonyl)acetophenone acetate

To a mixture of 10 g. of 5'-fluoro-2'-hydroxy-2-(methylsulfonyl)acetophenone and 50 ml. of acetic anhydride was added 0.5 ml. of pyridine, and the mixture was stirred for 1 hr. The resulting clear solution was poured into 800 ml. of ice water and the mixture was stirred for 1 hr. The precipitate was filtered off, washed with cold H_2O , and recrystallized from methanol; m.p. 116°-118°; yield 8 g. (68%); λ max $m\mu$ (ϵ) 229 (14,300), 300 (5,300); ν max 855 (m), 885 (ms), 910 (s), 995 (ms), 1015 (m), 1120 (s), 1170 (s), 1190 (s), 1210 (s), 1590 (m), 1680 (ms), 1695 (ms), 1765 (s) cm^{-1} .

Anal. Calcd. for $\text{C}_{11}\text{H}_{11}\text{FO}_5\text{S}$: C, 48.17; H, 4.04; S, 11.69. Found: C, 48.25; H, 4.02; S, 11.67.

EXAMPLE 14

2'-Hydroxy-3',5'-dimethyl-2-(methylsulfonyl)acetophenone

A mixture of 27 g. of 2'-hydroxy-3',5'-dimethyl-2-(methylsulfinyl)acetophenone, 1500 ml. of CHCl_3 , and 27 g. of m-chloroperbenzoic acid was stirred for one-half hr. The temperature rose to 45°. The solution was gently boiled for one-half hr., cooled in an ice bath, and stirred for 10 min. with 300 ml. of saturated NaHCO_3 solution. The organic phase was separated, and taken down to a crystalline residue under reduced pressure. The material was recrystallized from abs. ethanol; m.p. 182°-184°; yield 28 g. (96%); λ_{max} μ (ϵ) 216 (13,800), 271 (10,200), 363 (3,360); ν_{max} 825 (m), 1075 (m), 1170 (m), 1270 (m), 1635 (ms) cm^{-1} .

Anal. Calcd. for $\text{C}_{11}\text{H}_{14}\text{O}_4\text{S}$: C, 54.53; H, 5.82. Found: C, 54.63; H, 6.05.

EXAMPLE 15

2'-Hydroxy-3',5'-dimethyl-2-(methylsulfonyl)acetophenone acetate

A mixture of 10 g. of 2'-hydroxy-3',5'-dimethyl-2-(methylsulfonyl)acetophenone, 100 ml. of acetic anhydride and 0.5 ml. of pyridine was stirred for 18 hr. The clear solution was poured into 800 ml. of ice water, and the mixture was stirred for 1 hr. The precipitated was filtered off, washed with cold water, and recrystallized from methanol; m.p. 113.5°-115°; yield 8 g. (69%); λ_{max} μ (ϵ) 232 (22,000), 308 (4,800); ν_{max} 920 (m), 1080 (ms), 1135 (ms), 1170 (ms), 1210 (s), 1230 (s), 1690 (ms), 1745 (s), cm^{-1} .

Anal. Calcd for $\text{C}_{13}\text{H}_{16}\text{O}_5\text{S}$: C, 54.92; H, 5.67. Found: C, 54.80; H, 5.69.

EXAMPLE 16

2'-Hydroxy-3'-methyl-2-(methylsulfonyl)acetophenone

A mixture of 27 g. of 2'-hydroxy-3'-methyl-2-(methylsulfinyl)acetophenone, 27 g. of m-chloroperbenzoic acid and 600 ml. of CHCl_3 was stirred for one-half hr. The temperature rose to 45°. The mixture was gently boiled for one-half hr., chilled, and stirred for 10 min. with 200 ml. of saturated NaHCO_3 solution. The organic phase was separated and concentrated to an oil under reduced pressure. The oil was crystallized from abs. ethanol. The crystals were filtered and recrystallized from abs. ethanol; m.p. 100°-102°; yield 24 g. (85%); λ_{max} μ (ϵ) 214 (16,700), 268 (11,400), 347 (3,500); ν_{max} 780 (ms), 980 (m), 1140 (ms), 1230 (m), 1620 (ms) cm^{-1} .

Anal. Calcd. for $\text{C}_{10}\text{H}_{12}\text{O}_4\text{S}$: C, 52.62; H, 5.30; S, 14.05. Found: C, 52.36; H, 5.26; S, 14.31.

EXAMPLE 17

2'-Hydroxy-3'-methyl-2-(methylsulfonyl)acetophenone acetate

A mixture of 10 g. of 2'-hydroxy-3'-methyl-2-(methylsulfonyl)acetophenone, 50 ml. of acetic anhydride, and 0.5 ml. of pyridine was stirred for 1 hr. The solution was poured onto 800 ml. of ice water, and the mixture was stirred for 1 hr. The precipitate was filtered off, washed with cold water, and recrystallized from CH_3CN ; m.p. 142°-147°; yield 4 g. (31%); λ_{max} μ (ϵ) 226 (22,000), 297 (4,700); ν_{max} 800 (ms), 980 (m), 1075 (s), 1140 (s), 1195 (s), 1220 (s), 1685 (ms), 1745 (s) cm^{-1} .

Anal. Calcd. for $\text{C}_{12}\text{H}_{14}\text{O}_5\text{S}$: C, 53.32; H, 5.22; S, 11.86. Found: C, 53.59; H, 5.10; S, 11.88.

EXAMPLE 18

3'-Hydroxy-2-(methylsulfonyl)-2'-acetophenone

A mixture of 40 g. of 3'-hydroxy-2-(methylsulfinyl)-2'-acetophenone, 1,500 ml. of CH_2Cl_2 and 40 g. of m-chloroperbenzoic acid (Aldrich Chem. Co.) was stirred for 5 hr. The insoluble precipitate was filtered, and recrystallized from CH_3CN ; mp 201°-203°. yield 32 g (75%).

Anal. Calcd for $\text{C}_{13}\text{H}_{12}\text{O}_4\text{S}$: C, 59.08; H, 4.58; S, 12.13. Found: C, 58.83; H, 4.52; S, 12.17.

EXAMPLE 19

2'-Hydroxy-6'-methoxy-2-(methylsulfonyl)acetophenone

A mixture of 10 g. of 2'-hydroxy-6'-methoxy-2-(methylsulfinyl)acetophenone, 375 ml. of CHCl_3 and 10 g. of m-chloroperbenzoic acid (Aldrich Chem. Co.) was stirred for one-half hr. The temperature rose to 45°. The mixture was gently boiled for one-half hr., cooled to 25°, and stirred for 10 min. with 100 ml. of saturated NaHCO_3 solution. The organic phase was separated, and evaporated to a solid residue under reduced pressure. The residue was recrystallized from absolute ethanol; mp 152.5°-155.5°; yield 7 g (65%).

Anal. Calcd for $\text{C}_{10}\text{H}_{12}\text{O}_5\text{S}$: C, 49.17; H, 4.95. Found: C, 49.00 H, 5.20.

EXAMPLE 20

4'-Chloro-2'-hydroxy-2-(methylsulfonyl)acetophenone

To a solution of 18 g of 4'-chloro-2'-hydroxy-2-(methylsulfonyl)acetophenone in 600 ml of CHCl_3 was added 16.2 g of m-chloroperbenzoic acid (Aldrich Chem. Co.) with stirring. The temperature gradually rose to 37°. The solution was stirred for 10 min, and then gently boiled for 15 min, chilled, and stirred for 10 min with 200 ml of saturated NaHCO_3 solution. The organic phase was separated, and evaporated to a crystalline residue under reduced pressure. The material was recrystallized from ethyl acetate; mp 151.5°-153.5°; yield 12 g (63%); λ_{max} $\text{m}\mu$ (ϵ) 213 (17,700), 266 (13,000), 325 (4,800); ν_{max} 800 (m), 905 (m), 1080 (m), 1120 (m), 1155 (m), 1230 (m), 1620 (ms) cm^{-1} .

Anal. Calcd for $\text{C}_{12}\text{H}_{10}\text{ClO}_4\text{S}$: C, 43.47; H, 3.65; S, 12.89; Found: C, 43.63; H, 3.65; S, 13.16.

We claim:

1. A compound of the formula:

wherein R_1 and R_2 are hydrogen, lower alkyl having one to six carbon atoms, lower alkoxy having one to six carbon atoms, hydrocarbon aryl having six to 10 carbon atoms or halogen or R_1 and R_2 taken together with the benzene ring forming naphthalene.

2. A compound according to claim 1 which is 3'-hydroxy-2-(methylsulfonyl)-2'-acetonaphthone acetate.

45

3. A compound according to claim 1 which is 2'-hydroxy-6'-methoxy-2-(methylsulfonyl)acetophenone acetate.

4. A compound according to claim 1 which is 2'-hydroxy-5'-methyl-2-(methylsulfonyl)acetophenone acetate.

5. A compound according to claim 1 which is 3'-chloro-2'-hydroxy-2-(methylsulfonyl)acetophenone acetate.

10 6. A compound according to claim 1 which is 2'-hydroxy-3'-methoxy-2-(methylsulfonyl)acetophenone acetate.

7. A compound according to claim 1 which is 1'-hydroxy-2-(methylsulfonyl)-2'-acetonaphthone acetate.

8. A compound according to claim 1 which is 5'-fluoro-2'-hydroxy-2-(methylsulfonyl)acetophenone acetate.

9. A compound according to claim 1 which is 2'-hydroxy-3',5'-dimethyl-2-(methylsulfonyl)acetophenone acetate.

10 10. A compound according to claim 1 which is 2'-hydroxy-3'-methyl-2-(methylsulfonyl)acetophenone acetate.

11. 3'-chloro-2'-hydroxy-2-(methylsulfonyl)acetophenone.

12. 2'-hydroxy-3'-methoxy-2-(methylsulfonyl)acetophenone.

13. 1'-hydroxy-2-(methylsulfonyl)-2'-acetonaphthone.

14. 5'-fluoro-2'-hydroxy-2-(methylsulfonyl)acetophenone.

15. 3'-hydroxy-2-(methylsulfonyl)-2'-acetonaphthone.

16. 2'-hydroxy-6'-methoxy-2-(methylsulfonyl)acetophenone.

17. 4'-chloro-2'-hydroxy-2-(methylsulfonyl)acetophenone.
